UNITED STATES PATENT OFFICE.

SIMON W. WARDWELL, OF PROVIDENCE, RHODE ISLAND, ASSIGNOR TO
UNIVERSAL WINDING COMPANY, OF PORTLAND, MAINE, A CORPO-
RATION OF MAINE.

WINDING-MACHINE.

SPECIFICATION forming part of Letters Patent No. 740,958, dated October 6, 1903.

Application filed January 31, 1902. Serial No. 92,044. (No model.)

To all whom it may concern:

Be it known that I, SIMON W. WARDWELL, a citizen of the United States, and a resident of Providence, in the county of Providence and State of Rhode Island, have invented an Improvement in Winding-Machines, set forth in the annexed specification.

My invention relates to winding-machines, and pertains particularly to machines for winding wire and similar materials.

The object of my invention is to provide devices whereby wire may be wound, like thread, in self-supporting cops or packages and without injury to the surface of the wire or in the case of insulated magnet-wire of the insulation.

My invention is fully set forth in the accompanying specification and drawings, of which—

20 Figure 1 is an end elevation of a winding machine equipped with my invention; Fig. 2, a longitudinal elevation of the same; Fig. 3, a front view of the reciprocating guide and guide-supporting devices, showing the novel instrumentalities whereby the winding is arrested. Fig. 4 is a plan view of the same.

The winding devices are of well-known structure and will therefore not be described in detail. They comprise a rotating cop-
30 holder or winding-spindle *a*, a reciprocating guide *b*, a cam *c* to actuate the guide, a traverse-bar *d* to carry the guide and driven by the cam, a traverse-frame *e*, in which the traverse-bar is mounted and reciprocated, movable to and from the winding-spindle, and devices intermediate the spindle and the cam whereby the relative speed of the two is controlled.

The general structure of the guide, the traverse-bar, and connections whereby it is driven from the cam is fully described in my pending application, Serial No. 70,253.

The tube or core on which the wire is wound is secured to the winding-spindle by any adequate means, (indicated in the drawings as a screw for expanding the extremity of the spindle.)

Attached to the spindle *a* near the end of the traverse next to the machine is the disk

f, in the edge of which notches are cut at intervals, in which is secured the end of the wire preparatory to winding. The machine, as illustrated in the drawings, is adapted to wind insulated wire into "magnet-coils," as they are termed, and the large diameter of the disk *f* insures a sufficient length of projecting wire for connections that must be made in using the magnets. The wire is secured in the manner shown at *g*.

It is impossible for wire to draw over such sharp bends and turns as those over which yarn may be drawn. The point at which such sharp bends would occur in this machine is at the reciprocating guide, and to remedy it a sheave or guide-wheel *h* is employed in con-
65 junction with the guide *b* to so raise the wire from the latter that it shall pass through the eye or groove of the guide without the short bends that would occur were the wheel or sheave not employed. The wheel *h* is mount-
70 ed on the guide-holder *i* on ears or brackets either attached to said holder or formed integral therewith.

In winding coils for magnet and similar work it is advantageous to have the winding 75 stop each time at the end of the package at which the winding was started, so that both ends of the wire shall project from the same end of the finished coil.

Provision is made whereby the winding is arrested when the package wound has attained a given diameter in the sizing-screw *j*, which is mounted in a member of the stopping devices to be engaged by the traverse-frame *e* when it has swung back to a predetermined distance from the winding-spindle *a*.

In the traverse-frame and opposite the sizing-screw *j* is mounted a swinging member *k*, pivoted in a slot that opens into the guideway of the traverse-bar *d*. An ear *l* is formed 90 on the swinging member opposite the sizing-screw *j*, and the edge opposite the ear is so formed that when the traverse-frame is swung back and the ear *l* brought into engagement with the sizing-screw a projection *m* on the 95 traverse-bar engages the said edge, swings the member *k*, and shifts the member which carries the sizing-screw to cause the arrest of

the winding. This projection *m* is secured to the traverse-bar and travels in a groove *n* in the traverse-frame.

The supply-spool *o* is secured to a rotatable 5 spindle *p*, which is mounted in appropriate bearings on the bracket *q*, attached to the machine. Secured to the spindle is the circular brake-disk *r*, upon the periphery of which bears the brake *s*. The latter is carried on an arm *t*, which swings from the top of an arm *u*, projecting upward from the bracket *q*. At the extremity of another arm, *v*, projecting outward from the bracket *q*, is mounted the bell-crank lever *w*, from one 10 arm, *x*, of which is suspended the weight *z*, and to the other arm, *2*, is secured a spring *3*. The latter is secured by one end in an eye *4* of the arm *t*, which when the brake *s* bears on the disk *r* is normally in line with the axis 15 about which the lever *w* rocks. The other end of the spring is secured to a collar *5*, adjustable on the arm *2*. The degree of pressure with which the brake *s* is pressed against the disk *r* can obviously be varied by varying 20 the position of the lever-arm *2*. When in the position indicated by the dotted lines of Fig. 1, there is no pressure exerted between the brake and its disk, as the pull of the spring is directly toward the axis of the pin *6*, 25 on which the brake-arm swings, therefore exerting no tendency to swing it about that axis. If, on the other hand, the arm *2* were shifted into line with the axis of the disk *r*, the spring would act on the brake with the full strength 30 of its tension. As the spring acts upon the arm *2* in a line passing through the axis of the lever *w* it does not tend to rotate the latter about its axis, and hence the lever can be shifted to vary the brake-pressure with 35 practically no resistance to such movement. The weight *z* tends to rock the lever *w* into such position that the spring shall exert its maximum effect on the brake *s* and hold the arm *2* in contact and engagement with the 40 arm *7* of the lever *8*. The lever *8* is also mounted in the top of the arm *u* and is secured to a rock-shaft *9*, at the opposite end of which is secured a grooved sector *10*. A weight *11* is suspended from the latter by 45 means of a cord attached to the eye or hook *12*. A relatively long arm *13*, carrying a sheave or wheel *14*, serves as a slack-controller. The sheave *14* is maintained in the position indicated by the full lines by the weight 50 *11* and is limited in its movement under the action of the weight *11* by suitable means—in the structure shown by the arch *15* of the lever *8*—adapted to engage with the top of the arm *u*. 55 The operation of my machine is as follows: Preparatory to winding, the end of the wire is drawn from its spool on the supply-spindle *p*, over the take-up sheave *14* and the guide-sheave *h*, through the guide *b* to the winding-spindle *a*. When starting the machine, the pull on the wire incident to the start shifts 60 the position of the sheave *14*, causing the

pressure of the brake on its disk *r* to be relieved, permitting the supply to rotate more freely. Should the supply rotate too freely, 70 however, and cause the wire to slacken, the sheave *14* promptly shifts under the action of the weight *11* to maintain the wire taut and the tension uniform. As the sheave *14* shifts, the lower arm *7* of the slack-controlling or 75 take-up lever is correspondingly moved to vary the position of the brake-spring *3*, and thereby the direction of its action on the brake *s* and intensity of pressure of the latter on its disk *r*. If the resistance to delivery of the wire increases, the brake-pressure is relieved. If the delivery is too free, the brake-pressure is increased to restrain the rotation of the supply. As the package wound increases in diameter the traverse-frame 80 swings back toward the sizing-screw *j*. The latter engages the ear *l* and swings the member *k* into the path of travel of the projection *m*, which latter acts through the member *k* to shift the sizing-screw and cause the winding to be arrested at the same end of the package as that from which it was started. If for any reason it is desirable to withhold the brake from engagement with its disk, the arm *2* of the lever *w* can be swung to the 85 right, Fig. 1, of the position indicated by the dotted lines. The pull of the spring then shifts the brake-arm *t* from its normal position and the eye *4* from in line with the axis on which the lever *w* swings. The spring 90 then acts upon and swings both the lever *w* and the arm *t* to the right, overcoming the pull of the weight *z* until the two engage and their movement is arrested, thus removing and maintaining the brake *s* away from its 95 disk. To return it thereto, it is necessary simply to push the arm *2* to the left, Fig. 1, beyond the position indicated by dotted lines, when the eye *4* is again brought into line with the axis of the lever *w*, and the spring *3*, 100 again becomes neutral in its tendency to rock the lever *w*.

I am aware that controlling devices have been used before in which brake resistance or its equivalent has been applied with the 105 use of an elastic element and the degree of resistance varied, varying the intensity of the spring action on the brake. This has, however, been attained by varying the amount of extension, compression, and torsion of the 110 spring, which varied the degree of resistance of the take-up devices from whose movements the spring variation must necessarily be obtained.

With my improved structure the greatest 115 possible degree of variation in the brake-pressure may be obtained without effect on the take-up devices. The adjustments of the brake and of the take-up are independent and hence simple. The weight *z* is made of 120 sufficient amount to control the slack in the material wound without reference to the tension of the spring *3*, and vice versa.

I have shown the preferred embodiment of

my invention; but it is obvious that structural modifications may be made which would also embody the novel correlation of parts which constitute my invention, and also that 5 though the machine has been described as for wire winding it may be employed for winding other materials.

While I have referred to a magnet-coil consisting of covered wire wound as shown, I do 10 not here claim this peculiar form of coil.

Without limiting myself to the precise structure above disclosed, I claim as my invention—

1. The combination with the winding-spindle of a winding-machine, of a disk secured thereto having notches in its edge in which the wire is secured, preparatory to winding. 15

2. The combination in a winding-machine, with a rotating spindle and reciprocating 20 guide, of means for causing the winding to cease when the guide is at a predetermined point of its traverse.

3. The combination in a winding-machine with a rotating winding-spindle, a reciprocating guide, and devices for causing the winding to be arrested at a predetermined 25 diameter of the package wound, of devices for insuring that the reciprocating guide shall stop uniformly at the same end of the traverse. 30

4. The combination in a winding-machine with a rotating spindle, a reciprocating guide adapted to be moved away from the winding-spindle with the increasing diameter of the 35 package wound, and devices to be caused to act to stop the winding by the swinging back of the guide, of a movable member to be shifted by the reciprocation of the guide to engage said stopping devices and cause the 40 arrest of the winding when the guide is at a predetermined point in its traverse.

5. The combination in a winding-machine with a rotating winding-spindle, a reciprocating guide, a traverse-bar to carry the guide 45 and a frame in which the traverse-bar is carried and reciprocated, adapted to be swung back from the winding-spindle by the increasing diameter of the package wound, and a member to be shifted by the movement of the 50 swinging frame, to cause the arrest of the winding, of a movable member, carried in the swinging frame adapted to be shifted by the reciprocating traverse-bar to act on the stopping devices to arrest the winding at the 55 completion of the package and when the guide is at the same end of the package at which the winding was started.

6. A tension and supply controlling device 60 for winding-machines, comprising a rotating supply, a brake to control the rotation of the supply, and means for varying the intensity of the brake-pressure by varying the direction of action of the force applied to the brake to press it against the supply relative 65 to the direction of action of the brake on the supply.

7. A tension and supply controlling device

for winding-machines, comprising a rotating supply, a brake to control the rotation of the supply, a spring to cause the brake to act 70 upon the supply, and means for varying the degree with which it acts, by shifting the direction of the line of action of the spring.

8. A tension and supply controlling device 75 for winding-machines, comprising a rotating supply, a brake to control the rotation of the supply, mounted on a swinging arm, a spring attached by one end to the said arm and by the other to an arm of a lever whose axis is in line with the point at which the spring is 80 attached to the brake-arm, and devices acted on by variations in delivery of the material from the supply, to shift the said lever and vary the direction of the line of action of said spring. 85

9. The combination in a tension and supply controlling device with a rotating supply, of a brake to control the rotation of the supply, of a spring to actuate the brake, and a slack-controlling lever so arranged that any movement 90 due to an increased or decreased degree of slackness of the material delivered from the supply acts to so shift the spring that, without varying its length, it causes the brake to act with varying pressure. 95

10. The combination in a tension and supply controller of a rotating supply, a brake to control the rotation of the supply, a spring to actuate the brake and a slack-controlling lever so arranged that any movement thereof 100 due to an increased or decreased degree of slackness of the material delivered from the supply shifts the line of action of the spring to cause the brake to act with increased or decreased pressure. 105

11. The combination with a rotating member, a brake to control its rotation, and means to press the brake against the rotating member, of devices for varying the intensity of pressure of the brake by varying the direction of the application of said pressure to the brake relative to the direction of action of the brake. 110

12. The combination in a tension and supply controlling device, of a rotating supply, 115 a brake to control the rotation of the supply, a spring to cause the brake to act on the supply, connected by one end with the brake and by the other with a lever, and so mounted that its line of pull is always toward the axis 120 on which the lever turns.

13. The combination in a winding-machine with a winding-spindle, a rotating supply, a take-up lever intermediate the supply and the winding-spindle, and a weight to shift the 125 lever to deflect the wire from a direct course from the supply to the winding-spindle, of a brake to control the rotation of the supply, and a swinging arm to support the brake, a spring secured by one end to the swinging 130 arm to engage the brake with the supply, a lever to which the other end of the spring is adjustably secured, so mounted that in all operative positions the direction of pull of

the spring is in line with the axis on which it rocks, and a weight to maintain the said lever in engagement with the take-up lever, substantially as described.

5 14. The combination in a tension and supply controlling device, of a rotating supply, a brake-disk connected with the supply, a brake pressed into frictional engagement with the disk, means for applying pressure to the 10 brake, and for varying the intensity of its frictional engagement with the disk by varying the direction of the action of said means relative to the direction of action of the brake.

15 15. The combination in a tension and supply controlling device, of a rotating supply, a brake-disk connected with the supply, a swinging brake pressed into frictional engagement with the disk, and spring to press the brake against its disk, a lever to which 20 the spring is attached, and which is adapted to be rocked to so shift the line of pull of the spring that it may act directly toward the axis on which the brake swings, to produce no pressure of the said brake on its disk or 25 in such direction as to cause it to act and with a degree of pressure dependent on the direction of pull of the spring.

16. The combination in a tension and supply controlling device of a rotating supply, a 30 brake-disk connected with the supply, and a brake pressed into frictional engagement with the disk, a spring so mounted that the direction of its line of pull may be shifted from a

position in which it acts normal to the direction of movement of the brake to produce no 35 pressure of the latter on its disk, to a position in which it approaches the line of movement of the brake to exert a maximum action of the spring thereon, to press it into frictional engagement with its disk. 40

17. The combination in a tension-controller for unrolling supplies, of braking devices adapted to act at a uniform distance from the axis of rotation of the supply during its un-winding, a spring to cause frictional resistance between the contacting surfaces, and 45 means for shifting the direction of action of said spring to vary its degree of action.

18. The combination with an unrolling supply, of braking devices adapted to act at a 50 uniform distance from the axis of rotation of the supply to apply tension to the material being delivered, and means for varying the intensity of the friction of the contacting surfaces by varying the direction of the force 55 applied to cause the contact of said surfaces relative to the direction of action of the said braking devices.

In testimony whereof I have signed my name to this specification in the presence of 60 two subscribing witnesses.

SIMON W. WARDWELL.
